UNITED STATES PATENT OFFICE.

ARTHUR KIRKPATRICK, OF GRAND RAPIDS, MICHIGAN.

DESIGN FOR A CHAIR.

SPECIFICATION forming part of Design No. 31,513, dated September 12, 1899.

Application filed August 9, 1899. Serial No. 726,731. Term of patent 7 years.

To all whom it may concern:

Be it known that I, ARTHUR KIRKPATRICK, a citizen of the United States, residing at Grand Rapids, in the county of Kent and State of Michigan, have invented and produced a new and original Design for Chairs, of which the following is a specification, reference being had to the accompanying drawing, forming a part thereof.

As shown in the drawing, the leading or distinctive feature of my design consists in the broad flat rectangular arms, a closed rectangular structure beneath one arm, and an open rectangular structure beneath the other arm, said arms and structures projecting outward from the vertical line of the chair-legs.

A is the upholstered back of the chair; B, the upholstered seat of the same; C, the vertical posts or legs. D are broad flat rectangular arms projecting outward from the vertical plane of the legs; E, panels in the vertical plane of the legs closing the space between the arms and seat; F, a rectangular

box beneath the arm at one side; I, a bottom board below the outer arm and parallel thereto; G G, vertical panels connecting said arm and bottom board and extending at right angles to the panel E; II, a vertical panel parallel to the panel E and extending from the outer edge of the panel G forward at right angles to said panel, and J J are brackets extending outward from the front legs of the chair and beneath the box F and bottom board I.

Having described my invention, what I claim as new, and desire to secure by Letters Patent, is—

The design for a chair as herein shown and described.

In testimony whereof I affix my signature in presence of two witnesses.

ARTHUR KIRKPATRICK.
